SEMITRAILER BODY CONSTRUCTION

Harold H. Robinson, Coral Gables, Fla., and William J. Parrish, Detroit, Mich., assignors to Curtiss Aerocar Company, Inc., Coral Gables, Fla., a corporation of Florida

Application April 26, 1934, Serial No. 722,448

1 Claim. (Cl. 296—28)

This invention relates to automobile trailers of the type known as semi-trailers, in which the rear end of the trailer is supported by a pair of wheels and the front end by a swivel connection to the rear end of a tow car or tractor. More particularly it relates to the body framing of such semi-trailers wherein the body frame takes the form of a box girder similar to that shown in the patent to Curtiss 1,880,844.

It is among the objects of the invention to provide an improved truss frame structure which shall distribute and sustain the load and operating stress in an efficient manner and at the same time permit forward vision through unobstructed window openings without sacrifice of structural strength.

Other and further objects residing in the detail of the structural members will be apparent from the following specification and claim.

In the accompanying drawings which illustrate one embodiment of the invention:

Fig. 1 is a side view of a semi-trailer constructed according to the invention, the body covering being removed to show the framing;

Fig. 2 is a plan view of the structure, shown in Fig. 1, the top framing being partially broken away to show the floor structure;

Fig. 3 is a side view of the nose casting;

Fig. 4 is a rear view of the structure of Fig. 3;

Fig. 5 is a plan view of the structure of Fig. 3;

Fig. 6 is a sectional view substantially on line 6—6 of Fig. 3;

Fig. 7 is a fragmentary perspective view of the nose assembly;

Fig. 8 is a detail perspective view showing the manner of connecting the chord members;

Fig. 9 is a vertical sectional view of the connections of Fig. 8;

Fig. 10 is a perspective view showing the connection of the foremost post member with the lower chord members;

Fig. 11 is a detail view partly in section showing the connection of the intermediate chord to the foremost post member;

Fig. 12 is a fragmentary side view showing a modified floor structure; and

Fig. 13 is a plan view of the structure shown in Fig. 12.

Referring to the drawings, the body frame is shown in the form of a box-like girder, the sides of which are formed by trusses each comprising an upper chord 1, a lower chord 2 and an intermediate or belt chord 3, the latter acting as the major upper stress member of the truss as will later be more fully pointed out. Spaced vertical post members 6 connect the three chord members. The post members 6 as best shown in Figs. 8 and 9 are continuous between the upper and lower chords and as there shown are mortised a short distance into the upper chord as at 7 and

are further connected to the chord by means of T-shaped plates 9 set into aligned kerfs formed in the chord and the end of the post. Bolts 10 secure the plates 9 in position in the manner disclosed in co-pending application Serial No. 5 602,754, filed April 2, 1932.

The connection of the lower end of posts 6 to lower chord 2 is made by means of gusset plates 12, fitted in aligned kerfs formed in the members, and held therein by bolts 14 in accordance 10 with the practice described in detail in the above mentioned co-pending application. Web portions 15 of plates 12 are drilled as at 16 to receive one end of wires 17 which form the tension members of the truss.

The belt chords 3 are formed of two parallel members 3a and 3b. The outer member 3a is secured directly to the outer faces of the post 6 by wood screws 19. The inner member 3b is set into mortises 20 cut in the inner faces of the 20 post 6. Downwardly extending saw kerfs 21 are provided at the inner edges of the lower faces of the mortises to receive gusset plates 22. The gusset plates 22 extend beyond the sides of the posts 6 and the upper edges of the plates are bent 25 over as at 23 to engage the upper edge of the chord member 3b. Bolts 24 secure the plates 22 to the members 3b and the assembly is held in the mortise by a plate 26 secured to the post 6 by bolts 27. The plates 22 are drilled at 28 to receive one end of the wire tension members 17.

The upper chords of the respective trusses are converged beyond the foremost posts 6a and are connected to a metallic frame 30 later described. The intermediate or belt chords 3 similarly converge beyond posts 6a and are also secured to the frame 30. The portions 3c of chords 3 between posts 6a and frame 30 are in the form of a single member as best shown in Figs. 7 and 11. As shown in the latter figure, the forward ends of members 3a 40 and 3b are mortised into the post 6a and provided with a gusset plate 31 bent around the forward end of member 3b and bolted directly to the post 6a by means of a bolt 32. Member 3c is mortised into post 6a as at 33 and secured in 45 position in any suitable manner as by toe-nailing at 34.

Lower chords 2 are each connected to their respective posts 6a as shown in Fig. 10 by means of a gusset plate 36 and a washer plate 37, which 50 plates also serve to secure the upwardly curved, converging lower chord members 2a to the posts 6a. Referring to Fig. 10, the forward end of chord 2, the lower end of post 6a and the rear end of member 2a are provided with aligned saw 65 kerfs in which plate 36 fits. The lower edge of plate 36 is provided with a plurality of oppositely outwardly bent wings or tongues 39 which engage the lower face of chord 2 and the forward edge of said plate is provided with similar wings 40 60

engaging the underface of member 2a. Washer plate 37 is mortised into the inner faces of members 2, 6a and 2b, and bolts 41, passing through said members and the plates 36 and 37, form 5 therewith a substantially rigid joint at this point. The plate 36 is provided with an exposed triangular portion 42 drilled at 43 to form an anchorage for one of the wire tension members 41. It will be understood that the portions of plates 36 10 and 37 which are connected to members 2a are bent to accommodate the converging direction of these members.

The forward ends of members 2a are connected together in a coupling pin assembly substantially 15 like that shown in co-pending application Serial No. 663,947, filed April 1, 1933 to which application reference is made for the details of this connection. It is sufficient here to point out that the forward ends of members 2a are brought 20 together at the coupling post or pin 45 to which they are secured by means of a formed plate 46 bent around pin 45 and having top flanges 47 engaging the upper faces of members 2a and inwardly struck flanges 48 engaging the under face 25 of said members.

The frame 30 to which the chord members 1 and 3c are secured, presents the form of a rearwardly inclined inverted triangle, the apex of which is positioned at the upper end of the coupling pin and an aperture formed in the frame 30 receives the upper end of the coupling pin which is reduced in diameter as indicated at 51. Diverging angular flanges 53 are formed adjacent the apex of the frame to receive the ends of 35 chord members 3c. Bolts 55 secure the ends of members 3c to the flanges 53 and and bolts 56 passing through the members 3c, flanges 47 and member 2a rigidly connect frame 30; and the chords connected thereto to the coupling structure.

Angular extensions 57 formed at the upper corners of frame 30 are bolted as at 58 to the ends of chords 1. The side members of frame 30, the adjacent short posts 59 and those portions 45 of the chords 1 and 2c and post 6a, which frame the window openings in the nose portion of the vehicle, are provided with grooves 60 for the reception of window glass, as indicated in dotted lines at 66.

At the rear portion of the vehicle the lower chords 2 are interrupted as shown in Fig. 2 to form wheel wells A, inwardly offset frames 61 serving to transmit the stresses set up in the lower chords to the rear posts 62 of the trusses. The 55 rear post 62 extends only a short way above the belt chord 3 where it joins and is mortised into a forwardly inclined strut 64 which is secured to the lower chord 2 and belt chord 3 in the same manner as are posts 6. The upper end of strut 64 is connected to the upper chord 1 by a short inclined member 65. As will be clear from Fig. 1 post 62 and strut 64 form in effect a triangular abutment at the rear of the truss and that member 59 and the side of frame 30 together with the intervening portion of the intermediate chord, form a similar abutment at the forward end of the truss. The upper chord 1 extends between these abutments, supported at intermediate points by the posts 6. The traction stresses are in the 65 main taken by the lower truss structure; the fact that the posts 6 are continuous to the upper chord 1 together with the end construction above noted results, however, in the stresses being reflected and distributed through the upper portion of the 70 vehicle in a uniform manner so that shearing 75

stresses at the belt line are avoided and unobstructed window openings are provided at the nose portion and along the sides of the vehicle without weakening the frame as a whole.

Spaced roof bows 67 are secured to the chords 5 1 and struts 64 in any suitable manner, and the lower chords 2 are connected by spaced transverse floor beams 68.

In Figs. 12 and 13 is shown a modified floor structure for use where heavy duty is required. Reference characters 70 designate a pair of truss rods which extend substantially the full length of the floor frame. These truss rods pass through openings formed in the rearmost floor beam, the extending ends being provided with retaining 15 nuts 71. At their forward ends rods 70 pass through openings formed in metal castings 72 which secure the joint between the lower chord 13, foremost post 74 and upwardly curving chord extension 75. Nuts 76 hold the rods in the cast- 20 ings 72 and turnbuckles 77 provide means for properly tensioning the rods. The truss rods are positioned diagonally of the floor structure in order to clear the wheel well and are held in vertically bowed relation by brackets 78 secured to 25 the floor beams in any suitable manner. By properly tensioning the rods the floor frame may be bowed slightly upwardly if desired. Where truss rods 70 pass in proximity to the wheel axle 30 79, interference is avoided by using a drop axle wherein the central portion of the axle is below the center of the wheels. In disposing the truss rods 70 diagonally the points of rear attachment to the frame are brought relatively close together 35 and, to provide adequate bracing against compression, aligned spaces 80 are fixed between the floor beams 81, substantially parallel to and inside the truss rods 70.

We claim:—

The body frame for a semi-trailer vehicle which comprises spaced, vertical side trusses each truss having upper, lower, and intermediate chords, spaced vertical post members, connected at their upper and lower ends to the upper and lower 45 chords respectively and, at a point intermediate their ends, to the intermediate chord, to form upper and lower truss panels, diagonally arranged wire tension members secured in the lower truss panels, the forward portions of the intermediate 50 chords of the trusses being converged toward each other in a substantially horizontal plane, the forward portions of the upper and lower chords being respectively downwardly and upwardly converged and means for connecting the 55 forward ends of said chords together comprising an open frame having the form of a rearwardly inclined inverted triangle, forming an unobstructed window opening, vertical members connecting the upper and intermediate chords of the trusses 60 closely adjacent the meeting point of the upper chords and said frame, said members cooperating with the sides of the triangular frame and the intervening portion of the intermediate chords to form triangular abutments at the forward end of 65 the trusses, and a forwardly inclined strut at the rear of each truss connected intermediate its ends with the rearmost truss post to form with said rearmost truss post and the intervening portion of the lower chord, a triangular abutment 70 at the rear end of each truss, the upper chord of the trusses being restrained between said forward and rear abutments.

HAROLD H. ROBINSON.
